BIFURCATED LEG STRUCTURE OPTIONAL-
LY SUPPORTING LUGGAGE SECTIONS IN
HORIZONTAL OR IN VERTICAL AND HORIZONTAL POSITIONS

Mattie Louise Wallace, Los Angeles, Calif.

Application March 8, 1948, Serial No. 13,628

1 Claim. (Cl. 190—11)

1

This invention relates to baggage, and more particularly to an article of luggage which is convertible into an alternative form capable of affording convenience as a table.

Other features include the provision of detachable and longitudinally adjustable legs for said container which may be collapsed and stored or carried within the container when the latter is in folded position.

Another advantage resides in the provision of aligned socket members in the opposite sections of the foldable container, which sockets extend into the interior thereof without being in communication with the interior of the container so as to allow the insertion therein of collapsible and detachable legs without leaving any openings in the container's outer walls through which contents of the container otherwise might be lost and through which dust and moisture otherwise might enter.

A further object in this connection is so to design and arrange the sockets, as well as the portions of certain ones of the detachable supporting legs, that they operate to support the container optionally in either of two alternative positions of adjustment, one of which is with both its sections arranged horizontally, so that they co-operate with each other in serving as a flat-topped table, and the other of which is with one section horizontal and the other extending upwards from one edge of the horizontal section, thus affording convenience for use as a dressing table or make-up stand.

The invention is here illustrated by its embodiment in a suitcase or similar container and the provision of such a novel travelling bag is also among the purposes of the present invention which, however, is not to be limited in its scope to such embodiment.

Other objects and advantages of the invention will be apparent from the following description and claim, the novelty consisting in the features of construction, combination of parts, the unique relations of the members and the relative proportioning, disposition, and operation thereof, all as more completely pointed out in the appended claim.

In the drawings, which form part of the present specification:

Figure 1 is a perspective view of a foldable case or container embodying the principles of my invention.

Figure 2 is a perspective view of the container shown in open position and mounted upon its detachable and adjustable legs.

Figure 3 is a transverse, vertical sectional view taken through the supported container along the line 3—3 of Figure 2.

Figure 4 is an end elevational view drawn to

2

reduced scale and showing the container supported in a half-open or L-shaped position.

Figure 5 is a detail, fragmentary view in perspective, particularly showing the arrangement of the mounting sockets in adjacent corners of two halves of the container.

Figure 6 is a perspective view of the foldable case shown mounted upon its detachable legs in open position and provided with several separate compartments in each half of the case.

Figure 7 is a perspective view of the individual compartments of one side of the case, shown removed therefrom.

Figure 8 is a fragmentary vertical sectional view taken along the line 8—8 of Figure 7 and showing the manner of engagement of a removable compartment lid with an adjacent wall of its compartment.

Figure 9 is a fragmentary vertical sectional view taken along the line 9—9 of Figure 7, particularly showing the finger slot for lifting the closure lid of one of the compartments.

Figure 10 is a perspective view showing the lid of one of the side compartments of the group shown in Figure 7.

As illustrated, there is provided a generally rigid container 11 here shown as having the general form of a conventional suit case and comprising a pair of similar and confronting sections 12 and 14, hingedly connected along a common longitudinal edge 16, preferably each section being provided with a longitudinal, juxtaposed handle 18 and 20, respectively, along the outer face of the edge 21 opposite the hinged edge 16. The hinges 22 and 24 are disposed so that the bottom sides 26 and 28 of the two sections of the container will abut against each other when the case is opened to a horizontal position, in such position the upright walls of the two halves of the case serving thus to define a corresponding pair of open topped receptacles 30 and 32, as shown in Figures 2 and 3.

Formed integral with or attached to the adjacent side walls of the respective case sections 12 and 14, are three parallel socket members 34, 35, 36, and 37, 38, 39, respectively, opening to the outside and extending approximately the depth or height of the respective receptacle 30, 32. The first two of each trio of sockets are disposed at opposite ends of the respective bottom wall 26 or 28 so as to be located in downwardly opening, vertical position when the case is opened to a horizontal position as illustrated. The third socket 36, 39 of each trio is disposed adjacent the top wall of the associated section, midway between its ends. Whereas all of the sockets 34, 35, 36, 37, 38, and 39 are open at their outer ends, their inner ends are closed, thus precluding

50

55

any danger of losing articles from the container 11 therethrough, as well as entry of dust or moisture into the container's interior through any of the sockets.

Four collapsible legs are provided for insertion in the six sockets. The two straight legs 42 and 44 for the sockets 36 and 39 associated with the container's top walls are interchangeable with each other. These legs 42 and 44 are individually constructed of a pair of longitudinally telescoping members, of which the upper tubular member 46 has an outer diameter which permits its upper extremity to be detachably inserted more or less snugly within the socket 36 or 39, while the lower, usually solid rod 48 is of an external diameter corresponding generally to the inside of said tube so as to be slidably therein, being securely held at the desired position of extension by means of a set screw 50 threadedly mounted in the upper member.

The other two legs are also interchangeable with each other and are provided with a bifurcate upper portion 52 so that each leg may be inserted jointly in two adjacent sockets. The parallel ends 54 and 56 of these legs above the base of the fork are thus adapted to be inserted simultaneously into the juxtaposed sockets 34 and 37, or 35 and 38, as the case may be. The lower rod portion 53 is telescopically mounted within the tube 52 and retained at the desired location therealong by a set screw 60 similar to the assembly of the single legs. By this construction, the two upper arms 54 and 56 serve to brace the two sections 12 and 14 of the case in their open position with respect to each other.

In the alternative, as illustrated in Figure 4, when only one arm of the bifurcated support 52 is inserted in its socket, the adjacent parallel end may serve to support the opposite section 12 or 14 in an upright position by contact at its upper end with the outer face of the bottom wall 26 so that the two sections are supported approximately at right angles to each other or in a generally L-shaped position. Such arrangement may be of particular value, for example, on conserving space in a room or closet while still positioning the case in an open or accessible position. In other words, the upright section could be located against the side wall of a room or closet in this position and both sections would still be easily accessible for inserting and withdrawing articles as needed. When so arranged, the case would afford convenience as a dressing table or "make-up" stand.

When the two sections 12 and 14 are both supported in horizontal position, provision of a flat surface across their open top readily makes them useable as a serving table or stand. One such arrangement is illustrated in Figures 6 to 10, inclusive, wherein the two sections of the container are each provided with multiple compartments having individual flat covers for the several compartments. The section 14 is here shown provided with three individual receptacles or trays 62, 64 and 66 adapted to be nested within the cavity 32 and being generally rectangular except for curved portions adapted to conform to the outer curvature of an adjacent corner or median leg socket. The end trays 62 and 66 are provided with shallow dimples or recesses 68 along their inner surfaces adjacent their upper edge, while the lid member 70 is provided with correspondingly positioned lugs 72 adapted to seat within the recesses 68. In addition, the lid is provided with a sunken recess 74 in its upper face, undercut at one side thereof so as to enable the user to

insert a finger under the same and lift the lid thereby. The lids 78 may, if desired, be provided with one or more spring-pressed detents 80 adapted to seat in the adjacent socket 60.

It will be apparent that, particularly with this latter construction, individual compartments or trays may be used to store and transport a variety of articles which, of course, are in no wise necessarily limited to clothing. For instance, the present construction may be employed in providing food containers for picnics or the like, or again the several compartments may be used to store different games, cooking utensils, other apparatus such as physician's implements, or infant's clothing and accessories.

It will thus be evident that I have produced a foldable case of great adaptability which can be quickly and easily set up at any desired location, as well as readily adjusted for a variety of elevations.

While I have shown and described in some detail a presently preferred embodiment of my foldable case, it is to be understood that various modifications may be made in the construction and operation thereof within the scope of the subsequently claimed invention which is to be construed broadly and limited only by the prior art.

I claim:

- 30 An extensible container comprising a pair of hingedly interconnected sections, each of said sections having top, bottom, end, and side walls which form a receptacle shell, said sections being hingedly connected along adjacent edges of said bottom walls so as to be movable from a closed, vertical position to either a fully open position, in which the side wall of each of said sections assumes a horizontal position and said top, bottom and end walls extend upwards from said side walls, or to a half open position, in which one of said sections remains vertical and the other of said sections is pivoted from a vertical to a horizontal position, sockets located adjacent each of said bottom walls and adjacent at least one of said top walls of the case and opening downwards when each section is horizontally disposed, and detachable legs adapted to be inserted in said sockets so as to support the open container in an elevated position, said legs including at least one bifurcate leg, one of said leg furcations being insertable in one of said bottom wall sockets, and the other furcation being selectively insertable in the adjacent bottom wall socket when said sections have assumed a fully open position, or disposed against the outside surface of the bottom wall of that section which remains vertical when said sections assume a half-open position.

MATTIE LOUISE WALLACE.
